DESIGN FOR A STAIR TREAD

Louis Galtieri, Garfield, N. J.

Application March 7, 1940, Serial No. 90,748

Term of patent 14 years

To all whom it may concern:

Be it known that I, Louis Galtieri, a citizen of the United States, residing at the city of Garfield, in the county of Bergen and State of New Jersey, have invented a new, original, and ornamental Design for Stair Tread, of which the following is a specification, reference being had to the accompanying drawing, forming part thereof.

The figure is a perspective view of a stair tread

showing my new design, the essential features of which reside in the division of the surface thereof into panels of the size and arrangement as shown, said panels being of contrasting color.

I claim:

The ornamental design for a stair tread, substantially as shown and described.

LOUIS GALTIERI.
